(57) **CLAIM**

The ornamental design for a pouch hiding toy, as shown and described.

DESCRIPTION

FIG. 1 is a first perspective view of our pouch hiding toy;

FIG. 2 is front view thereof;

FIG. 3 a back view thereof;

FIG. 4 is a right side view thereof;

FIG. 5 is a left side view thereof;

FIG. 6 is a top view thereof; and,

FIG. 7 is a bottom view thereof.

As illustrated in FIGS. 1-5 and 7, in some examples a bell is attached to the end of the pouch.

The dotted light broken lines within the body of the pouch hiding toy show surface ornamentation that forms no part of the claimed design. The broken lines showing an attached bell at the bottom of the pouch hiding toy show environmental structure that forms no part of the claimed design. All other broken lines illustrate stitching of the pouch hiding toy that forms no part of the claimed design.
